ELECTRONIC TIMING CIRCUIT

Henry M. Merrill, Chicago, Ill., assignor to J. P.
Seeburg Corporation, Chicago, Ill., a corpora-
tion of Illinois

Application August 17, 1945, Serial No. 611,187

7 Claims. (Cl. 250—27)

1

This invention relates to timing circuits and has for its principal object to provide a timing circuit which will give uniform results with a high degree of accuracy notwithstanding wide variations of voltage in the power supply.

The present invention is particularly adapted for use with bombing controls. A manual actuation initiates the opening of the bomb bay doors and the operation of the timing circuit. At the end of its time period the circuit initiates the operation of the intervalometer or other bomb dropping mechanism. The accuracy of bomb placement depends upon the accuracy of the timing circuit. Error ought to be less than .05 second in a 4 second interval, and this accuracy must be maintained although the voltage, normally provided by storage batteries, may vary between 25 and 30 volts.

The timing circuit hereinafter described and claimed exceeds these requirements. While it is particularly well adapted for the specific purpose referred to, it is, of course, capable of use for timing purposes generally.

The invention will readily be understood from the following description of a preferred embodiment thereof taken in conjunction with the accompanying drawing which is a wiring diagram thereof.

Referring to the drawing, the reference numeral 1 designates the positive line and the reference numeral 2, the negative line. The "start" button 3, when actuated manually, closes the switch 4, of the first control circuit, which may for example initiate the opening of the bomb bay doors. The button 3 also closes the switch 5 energizing the relay 6 which closes the contacts 7. The relay 8 is closed and is locked up by the normally open contacts 9 in series with the normally closed contacts 10.

A contact 11 connected to the negative line 2 normally engages a contact 12 which is connected to the line 13. When the relay 8 is energized this engagement is broken and the contact 11 engages the contact 14 which is connected to the line 15. The line 15 is connected to the left-hand side of the condenser 16, through the resistor 17 to the line 1, and to the cathodes 18 of the double tetrode 19. The line 13 is connected to the right-hand side of the condenser 16, through the resistor 20 to the line 1, and to the control grid of the upper tetrode. The control grid of the lower tetrode is connected through a C battery 21 to the movable arm of a voltage divider 22 whose resistor is connected between the lines 1 and 2. The screen grids of the two tetrodes

2

and the plate of the lower tetrode are connected through a resistor 23 to the line 1. The plate of the upper tetrode is connected through the winding of the relay 24 to the line 1. The relay 24 controls the normally closed contacts 10 and the normally open contacts 25 which are in the second control circuit which controls the operation which is to be performed at a certain time after the actuation of the button 3.

10 The tube employed may suitably be a 28D7 tube and the condenser 16 may suitably be a 10 microfarad condenser. For a four second period the resistor 20 may suitably have a value of 740,000 ohms. Suitable values for the resistors 17, 23 and 22, are 10,000, 2,400, and 1,000 respectively. The battery 21 is suitably a five cell battery applying approximately 7½ volts negative bias to the lower control grid.

Normally the left-hand side of the condenser 20 16 is positive and the right-hand side is negative. When the "start" button 3 is actuated, the relays 6 and 8 are energized and the latter is locked up by the contacts 9 and 10. The closing of the switch 4 starts the first operation. When the button 3 is actuated the left-hand side of the condenser 16 is connected to the negative line 2 by the contacts 11 and 14 and the right-hand side of the condenser 16 is connected to the positive line 1 through the high resistance 20. The charge on the condenser is thus reversed gradually and the voltage on the line 13 builds up in the positive direction and the plate current through the relay 24 builds up until it is strong enough to actuate the relay. If the voltage across lines 1 and 2 is low it will take a longer time for the plate current to build up to relay actuating strength, and vice versa. The upper tetrode is therefore compensated by a voltage derived from the lower tetrode. This voltage is derived from the output circuit of the lower tetrode and is applied to the upper screen grid. The lower tetrode provides a voltage which increases the plate current of the upper tetrode when the voltage across lines 1 and 2 is low and vice versa, as will now be described.

40 The voltage on the lower control grid is the algebraic sum of the negative voltage provided by the battery 21 and the positive voltage provided by the voltage divider 22. When the relay 8 is energized the cathodes are connected to line 2. Consequently the lower tetrode provides plate current and there is a certain voltage drop across the resistor 23. Thus the screen grid of the upper tetrode has a somewhat lower voltage 50 than the line 1. When the voltage across lines 55

1 and 2 is low the voltage of the control grid of the lower tetrode is more negative. There is a smaller plate current and the voltage of the upper screen grid is higher. As has been pointed out above the lower voltage across lines 1 and 2 tends to extend the period before the energization of the relay 24 and the higher voltage applied to the upper screen grid tends to compensate by increasing plate current of the upper tetrode. The degree of compensation can be adjusted to the optimum by means of the voltage divider 22. The value of the resistor 20 controls the period for which the timing circuit is set and this period may be adjusted by adjustment of the resistor.

Thus notwithstanding wide variations in voltage between the lines 1 and 2 I can attain the desired timing period, for example 4 seconds consistently with an error of considerably less than .05 second.

The employment of a single envelope containing two tetrodes is merely incidental. Any equivalent thermionic tube or tubes may be employed. The fundamental feature of the invention is that I have one thermionic means associated with the timing circuit and subject to error resulting from variation of the supply voltage. To correct this error I derive a corrective voltage from another thermionic means which voltage also varies with the supply voltage and I supply this corrective voltage to the first thermionic means so as to get a standard timing period.

Although the invention has been described in connection with the specific details of a preferred embodiment thereof, it must be understood that these details are not intended to be limitative of the invention except in so far as set forth in the accompanying claims.

Having thus described my invention I declare that what I claim is:

1. In combination, an R. C. timing circuit, thermionic means arranged to receive a control voltage from said circuit and having a plate circuit including a responsive load device actuatable when the plate current of said means is built up to a definite actuating degree after a desired period of time, a second thermionic means having a loaded plate circuit, control means in first said thermionic means connected to the plate of the second thermionic means a variable source of voltage arranged to energize said thermionic means, actuatable means for applying said source voltage across said R. C. circuit, a control means for the second thermionic means including a bias battery and a voltage divider connected across said source, in series with said battery, whereby the plate current of the second thermionic means is low and the control voltage it applies to the first thermionic means is high when the voltage of the source is low, said elements being correlated whereby the period is substantially uniform over a wide range of variation of the voltage of the source.

2. In combination, an R. C. timing circuit, thermionic means having a control grid connected to said R. C. circuit and a plate circuit including a responsive load device actuatable when the output current builds up to an actuating degree after a desired period, said thermionic means including a second control grid, a second thermionic means having its output circuit connected to the second control grid and including a third control grid, a resistor in the last mentioned output circuit whereby the voltage of the second control grid is diminished with increase of the

second output circuit, a source of direct current of variable voltage energizing said thermionic means, actuatable means for connecting said source across said R. C. circuit, a negative bias battery connected to the third control grid and a voltage divider connected across said source applying a predetermined fraction of the source voltage to the positive terminal of said battery, whereby the voltage applied to the second control grid is greater when the supply voltage is low, thus compensating for the build-up of the output voltage of the first thermionic means due to low voltage supply, whereby said period is made substantially uniform for wide variation of the supply voltage.

3. In combination, an R. C. timing circuit comprising a capacitor and a high resistor in series, means normally connecting the capacitor across a source of direct current of variable voltage, actuatable means for connecting the condenser and resistor to said source with opposite polarity whereby the condenser discharges and recharges in the opposite direction, a thermionic means energized by said source and having a control grid connected to an intermediate point of said circuit and a plate circuit including a responsive load device actuatable when the plate current builds up to an actuating degree after a period of time, which period of time tends to increase with lowering of the voltage of the source, a second thermionic means energized by said source and including a control grid and a loaded plate circuit whereby its plate voltage drops with increase of plate current, an additional control grid in the first thermionic means connected to the plate of the second thermionic means, adjustable means associated with said source for increasing the voltage of the control grid of the second thermionic means when the source voltage is high, increasing the plate current of the second thermionic means and lowering the voltage of the additional control grid of the first thermionic means, whereby the voltage of the additional control grid of the first thermionic means compensates for the tendency of the period to vary with variation of the voltage of the source.

4. In combination, an R. C. timing circuit comprising a capacitor and a high resistor in series, means normally connecting the capacitor across a source of direct current of variable voltage, actuatable means for connecting the condenser and resistor to said source with opposite polarity whereby the condenser discharges and recharges in the opposite direction, a thermionic means energized by said source and having a control grid connected to an intermediate point of said circuit and a plate circuit including a responsive load device actuatable when the plate current builds up to an actuating degree after a period of time, which period of time tends to increase with lowering of the voltage of the source, a second thermionic means energized by said source and including a control grid and a loaded plate circuit whereby its plate voltage drops with increase of plate current, an additional control grid in the first thermionic means connected to the plate of the second thermionic means, means for applying a bias to the control grid of the second thermionic means including a negative bias battery and a voltage divider connected across the source for supplying a positive voltage to said battery, whereby the voltage of the control grid of the second thermionic means is increased by increase of voltage of the source and the voltage applied to the additional control

grid of the first thermionic means is lowered, whereby said period of time is rendered substantially uniform with wide variation of the voltage of the source.

5. In combination, an R. C. timing circuit, thermionic means having a control grid connected to an intermediate point of said circuit, a second control grid, and a plate circuit including a responsive load device, a second thermionic means having a plate and a loaded plate circuit, a conductive connection between the plate of the second thermionic means and the second grid, a source of direct current of variable voltage energizing both thermionic means, and actuatable means for connecting said R. C. circuit across said source.

6. In combination, an R. C. timing circuit, thermionic means having a control grid connected to an intermediate point of said circuit, a second control grid, and a plate circuit including a responsive load device, a second thermionic means having a plate and a loaded plate circuit, and a third control grid, a conductive connection between the plate of the second thermionic means and the second grid, a source of direct current of variable voltage energizing both thermionic means, actuatable means for connecting said R. C. circuit across said source, and means for supplying bias to the third control grid including a battery and means in series with the battery for supplying an opposed voltage from said source

of magnitude depending upon the voltage of said source.

7. In combination, an R. C. timing circuit, thermionic means having a control grid connected to an intermediate point of said circuit, a second control grid, and a plate circuit including a responsive load device, a second thermionic means having a plate and a loaded plate circuit, and a third control grid, a conductive connection between the plate of the second thermionic means and the second grid, a source of direct current of variable voltage energizing both thermionic means, actuatable means for connecting said R. C. circuit across said source, and means for supplying bias to the third control grid including a battery having its negative terminal connected to the third grid and a voltage divider across said source having an intermediate point connected to the positive terminal of said battery.
